UNITED STATES PATENT OFFICE.

WILLIAM H. MINER, OF CHAZY, NEW YORK.

ROLLER SIDE BEARING.

1,252,358.

Specification of Letters Patent.

Patented Jan. 1, 1918.

Application filed July 21, 1916. Serial No. 110,479.

To all whom it may concern:

Be it known that I, WILLIAM H. MINER, a citizen of the United States, residing at Chazy, in the county of Clinton and State of New York, have invented a certain new and useful Improvement in Roller Side Bearings, of which the following is a full, clear, concise, and exact description, reference being had to the accompanying drawings, 10 forming a part of this specification.

This invention relates to improvements in roller side bearing.

One object of the invention is to provide a simple, relatively cheap roller side bearing for railway cars and so arranged that the roller will be automatically returned to central or normal position after each actuation.

Another and more specific object of the invention is to provide an improved roller side bearing having a roller under spring control whereby it is returned to normal position after each actuation, the springs being mounted on horizontally extended supporting rods.

In the drawing forming a part of this specification, Figure 1 is an end elevation of portions of two car bolsters showing my improved side bearing in connection therewith. 30 Fig. 2 is a longitudinal sectional view of the improved side bearing and taken on the line 2—2 of Fig. 1. Fig. 3 is a top plan view of the side bearing proper. Fig. 4 is a transverse, vertical sectional view taken on the line 4—4 of Fig. 2. Fig. 5 is a view corresponding to Fig. 2 but illustrating a different embodiment of the invention. Fig. 6 is a view similar to Fig. 3 and illustrating a still different embodiment of the invention. 40 And Fig. 7 is a transverse, vertical sectional view taken on the line 7—7 of Fig. 6.

In said drawing, 10 denotes the body bolster and 11 the truck bolster which are pivotally connected at their centers in the usual manner. As shown, the body bolster is provided with a striking plate 12 and the truck bolster has applied thereto the improved side bearing designated generally by the reference A.

50 The improved side bearing A preferably comprises a base member or casting B which is riveted or otherwise suitably secured to the truck bolster, and an anti-friction roller C. The base member B is of substantially box-like form, open at the top, and has outwardly extended bottom flanges 13 through

which pass the securing means, and on its interior, the base member is provided with a suitable inserted tread or wear plate 14 on which the roller C operates.

In the construction illustrated in Figs. 1 to 4, the member B is provided with parallel side walls 15—15 and end walls 16—16, the latter having hollow bosses 17 formed thereon within which are seated the ends of 65 springs 18—18. The springs 18 are mounted on a longitudinally extending, preferably rectangular bar 19, the latter having its ends supported by said bosses 17, the bar being held in proper position by nuts 20 threaded 70 on the ends thereof. Each of the springs 18 has its inner end seated on a boss 21 formed on a follower or shoe 22, the latter being curved on its inner face as indicated at 23 to fit the surface of the roller C. As shown, 75 the roller C comprises two sections C C¹ connected by a central section 24 of reduced diameter, thereby forming a slot or channel through which extends said bar 19. In this way, the bar 19, the springs and followers 80 carried thereby are located below the top surface of the base member B and furthermore, the bar 19 acts as a retaining means to hold the roller C in operative position.

In operation, as the roller C is rotated to 85 one side or the other of its central position, the corresponding spring 18 will be compressed. Upon release of the pressure on the roller C, said spring will immediately expand and force the roller C back to its central or normal position. In this operation, 90 the followers 22 will act as brakes on the roller and will thereby project the roller bodily without rotating it during the return of the roller to normal position. In this 95 manner, the roller C is constantly shifted in its position, thereby continually changing the surfaces brought into play and prolonging the life of the roller. By making the bar 19 square and the recess in the followers 22 100 of corresponding shape, the latter are prevented from rotating or becoming otherwise displaced with respect to the roller. It is apparent from the foregoing that replacement or repairs of the parts may be easily 105 effected since all that is necessary is to remove the bar 19.

Referring now to the construction illustrated in Fig. 5, the base member B¹ is substantially the same as the base member B 110 except that the pockets for the springs 118—118 are somewhat lower down. The

roller C¹ is made substantially the same, but instead of using a single bar, I preferably employ two bars 119—119. One of these is located above and the other below the connecting section 124 of the roller and the spring followers 122—122 are mounted between said bars 119 instead of on them. To properly guide the followers 122, the same are provided on their top and bottom edges with recesses 123 slidably fitting the bars 119. The operation of the parts will be understood from the more detailed description given of the structure illustrated in Figs. 1 to 4.

In the modification shown in Figs. 6 and 7, the base casting B² has each of its end walls provided with two hollow bosses 217—217, located in the corners of the casting and within which are received the ends 20 of four springs 218—218. The latter are mounted on a pair of rods or bars 219 having their ends supported in the ends of the base casting and slidably mounted on said rods 219 are the followers 222. Each of the 25 latter has a central portion 223 which fits the roller C² and operates in the same manner as the spring followers 22. In this construction, the roller C² is made of the same diameter throughout its entire length since the 30 central recess is not necessary because the bars 219 are arranged at the sides of the roller. If desired, the metal may be saved by coring the roller C² as indicated at 50.

From the preceding description, it will be seen that I have provided a roller side bearing which may be relatively cheaply manufactured; wherein is employed a roller of comparatively large diameter presenting a wide bearing surface; and wherein the roller 40 is always returned automatically to normal position after each actuation.

I claim:

1. In a roller side bearing, the combination with a retaining member, and a roller longitudinally movable therein, of means for returning said roller to normal position after actuation thereof, said means comprising,

Copies of this patent may be obtained for five cents each, by addressing the "Commissioner of Patents, Washington, D. C."

a rod arranged at right angles to the axis of the roller and having its ends mounted in said retaining member and detachable therefrom, springs located on opposite sides of the roller, and spring followers guided by said rods and frictionally engaging said roller, said rod preventing removal of the roller from the retaining member. 50 55

2. In a roller side bearing, the combination with a retaining member, and a roller longitudinally movable therein, of means for returning said roller to normal position after actuation thereof, said means comprising, a rod arranged at right angles to the axis of the roller and having its ends mounted in said retaining member and detachable therefrom, springs located on opposite sides of the roller, and spring followers guided by said rods and frictionally engaging said roller, said retaining member being provided with pockets within which said springs are seated. 60 65

3. In a roller side bearing, the combination with a retaining member, of an anti-friction roller longitudinally movable therein, of means for returning said roller to normal position after actuation thereof, said means comprising a rod arranged at right angles to the axis of the roller and having its ends mounted in said retaining member, and spring means mounted on said rod and acting on said roller, said roller comprising two sections united by an intermediate section of reduced diameter and said rod extending within the space provided between said two sections, the section of reduced diameter being disposed between said rod and the retaining member whereby said rod is adapted to hold the roller in position with respect to the retaining member. 70 75 80 85

In witness that I claim the foregoing I have hereunto subscribed my name this 18th day of July 1916.

WILLIAM H. MINER.
